CLAIM

The ornamental design for a pest repeller as shown and described.

DESCRIPTION

FIG. 1 is a front side perspective view of a pest repeller showing my design;

FIG. 2 is a front view of my design;

FIG. 3 is a rear view of my design;

FIG. 4 is a left side view of my design;

FIG. 5 is a right side view of my design;

FIG. 6 is a top view of my design; and,

FIG. 7 is a bottom view of my design.

The broken lines represent portions of the pest repeller that form no part of the claimed design.

1 Claim, 7 Drawing Sheets(56)
